UNITED STATES PATENT OFFICE.

LEWIS C. STEELE, OF COLUMBUS, OHIO.

CIRCUIT-BREAKER.

No. 920,208.

Specification of Letters Patent.

Patented May 4, 1909.

Application filed August 16, 1907. Serial No. 388,801.

To all whom it may concern:

Be it known that I, LEWIS C. STEELE, citizen of the United States, residing at Columbus, in the county of Franklin and State of Ohio, have invented certain new and useful Improvements in Circuit-Breakers, of which the following is a specification.

My invention relates to circuit breakers of that class which are particularly adapted for use in temporarily interrupting a current on a line wire for testing purposes and the objects of my invention are to provide a simple, reliable and effective circuit breaking or current interrupting device the use of which will obviate the necessity of cutting the wire and which may be easily and quickly operated and to produce other improvements in details of construction and arrangement of parts which will be more fully pointed out hereinafter. These objects I accomplish in the manner illustrated in the accompanying drawing, in which—

Figure 1 is a view in elevation of an insulator showing my improved circuit breaking device connected therewith, Fig. 2 is a central vertical section of the same on line $x-x$ of Fig. 1, Fig. 3 is a reduced transverse section on line $y-y$ of Fig. 1, Fig. 4 is a central vertical section of the circuit breaking device showing the same inverted with reference to the view shown in Fig. 2, and Fig. 5 is a detail view in perspective of a binding member which I employ as hereinafter described.

Similar numerals refer to similar parts throughout the several views.

1 represents a line wire such as is used for conducting electric current for telephone, telegraph and other purposes. This wire is adapted, as shown, to be looped about the ordinary form of insulator body 2, in which position it is secured by any suitable or well known means. From the point of its connection with the insulator, the wire 1 is provided with an extension of suitable length which is indicated at 1^a and which has a flexible terminal section 1^b , adapted to be connected with one end of my improved circuit breaking device, which I will now proceed to describe. This circuit breaker consists of a tubular body 3 which may be formed of glass, porcelain, properly treated fiber or other suitable insulating material. Into one end of the tubular or cylindrical body thus provided is inserted a metallic contact plug 4 which has an outer end socket 4^a adapted to

receive a wire end. The inner end portion of the plug 4 extends slightly within the tube 3 and at the opposite end of said tube is inserted a second plug 5 which has its inner end portion provided with a reduced extension or contact pin 5^a which terminates a desirable distance from the inner end of the plug 4 and which results in the formation of an annular space between said pin extension and the inner surface of the tube 3. The plug 5 is provided with a wire receiving socket 5^b . As indicated at 6 the tubular body 3 is provided with a centrally fixed exterior collar, from which projects laterally a headed pin or stud 7.

8 represents an elongated binding plate or strip, at the center of the length of which is formed an opening through which passes the projecting pin 7, the head of the latter being preferably riveted or forced into frictional engagement with the outer surface of the plate 8. This binding strip has formed therewith and extending centrally therefrom oppositely located arms 8^a each of which terminates in a short lateral projection 8^b having its end formed with a curved recess. Through the medium of wires 9 each of which has one of its ends connected with one end of the plate 8 and which wires are bound about the insulator 2, the tube 3 is securely held in a vertical position against the outer surface of said insulator, as shown in Figs. 1 and 2 of the drawing. And in order to insure the position of the tube against the insulator the recessed ends of the arm terminations 8^b are caused to engage the periphery of the tubes above and below the binding plate as shown in Fig. 2 thus locking the tube against accidental reversal.

10 represents a line wire which is suitably bound about the insulator 2 at a desirable distance from line wire 1. This wire 10, has an extension 10^a , terminating in a flexible wire section 10^b which has its end portion inserted and properly secured in the socket 4^a of the tube end plug 4, while the end of the section 1^b is similarly connected with the plug 5.

Within the tube I provide a body of mercury which is indicated at 13, the same being in sufficient quantity to insure a complete electrical connection between the plug 4 and the extension 5^a of the plug 5 when the tube 3 is in the upright position shown in Figs. 1 and 2, but of insufficient quantity to form a connection between the parts mentioned

when the tube is reversed, as shown in Fig. 4, in which position it is obvious that the mercury will be contained in the annular space between said plug extension and the wall of the tube.

The method of utilizing my invention is substantially as follows: Assuming that the tube is in the upright position shown in Fig. 1 and that it is desired to open the circuit at 10 that point for the purpose of testing between the insulator and a given point, or for any other temporary purposes, the tube 3 may be readily rotated on its pin 7 until the upper portion of the tubular body 3 engages in the 15 lower indentations 8^b of the plate 8, thus causing the mercury to assume the position shown in Fig. 4 of the drawing and thereby effectually breaking the circuit which normally exists when the tube is in the upright 20 position. The test having been made, it is obvious that the circuit may be again quickly closed by reversing the position of the tube 3. It is to be understood that the arms 8^a will 25 yield sufficiently to permit the above described action.

From the construction and operation described, it will be understood that my improved circuit breaker may be produced and adapted for use at a comparatively low cost and that its use will obviate the necessity of 30 cutting and again reuniting the wires for testing purposes.

What I claim, is:

In a device of the character described the combination with a tubular body portion of 35 plugs closing the opposite ends of said body portion, one of said plugs having a reduced portion which extends into the body portion, electrical conductors connected to said plugs, a binding plate comprising lugs having recesses formed therein, said lugs being adapted to frictionally engage said body portion and means for pivoting said body portion to said binding plate.

In testimony whereof I affix my signature 45 in presence of two witnesses.

LEWIS C. STEELE.
